UNITED STATES PATENT OFFICE

151,806

DESIGN FOR A COMBINED TELEPHONE STAND AND PAD HOLDER

Sol J. Beitch and Samuel Fine, New York, N. Y.

Application September 8, 1947, Serial No. 141,240

Term of patent 7 years

(Cl. D26—14)

To all whom it may concern:

Be it known that we, Sol J. Beitch, a citizen of the United States of America and a resident of the city of New York, county of Kings, and State of New York, and Samuel Fine, a citizen of the United States of America and a resident of the city of New York, county of Kings, and State of New York, have invented a new, original, and ornamental Design for Combined Telephone Stand and Pad Holder, of which the following is a specification, reference being had to the accompanying drawing, forming a part thereof.

We claim:

The ornamental design for a combined telephone stand and pad holder, substantially as shown.

SOL J. BEITCH.
SAMUEL FINE.
